(57) **CLAIM**

The ornamental designs for an emergency power supply with casing and plug, as shown and described.

DESCRIPTION

FIG. 1 is a front perspective view of the combined power supply, the casing and the plug.

FIG. 2 is a front view of the design for the power supply, shown apart from the plug and casing for ease of illustration;

FIG. 3 is a rear view of the design for the power supply, shown apart from the plug and casing for ease of illustration;

FIG. 4 is a left side view of the design for the power supply, shown apart from the plug and casing for ease of illustration; FIG. 5 is a right side view of the design for the power supply, shown apart from the plug and casing for ease of illustration; FIG. 6 is a top view of the design for the power supply, shown apart from the plug and casing for ease of illustration; FIG. 7 is a bottom view of the design for the power supply, shown apart from the plug and casing for ease of illustration; FIG. 8 is a front perspective view of the design for the power supply, shown apart from the plug and casing for ease of illustration;

FIG. 9 is a front view of the design for the casing, shown apart from the power supply and plug for ease of illustration; FIG. 10 is a rear view of the design for the casing, shown apart from the power supply and plug for ease of illustration; FIG. 11 is a left side view of the design for the casing, shown apart from the power supply and plug for ease of illustration; FIG. 12 is a right side view of the design for the casing, shown apart from the power supply and plug for ease of illustration;

FIG. 13 is a top view of the design for the casing, shown apart from the power supply and plug for ease of illustration; FIG. 14 is a bottom view of the design for the casing, shown apart from the power supply and plug for ease of illustration; FIG. 15 is a front perspective view of the design for the casing, shown apart from the power supply and plug for ease of illustration;

FIG. 16 is a front view of the design for the plug, shown apart from the power supply and casing for ease of illustration;

FIG. 17 is a rear view of the design for the plug, shown apart from the power supply and casing for ease of illustration; FIG. 18 is a left side view of the design for the plug, shown apart from the power supply and casing for ease of illustration;

FIG. 19 is a right side view of the design for the plug, shown apart from the power supply and casing for ease of illustration;

FIG. 20 is a top view of the design for the plug, shown apart from the power supply and casing for ease of illustration; FIG. 21 is a bottom view of the design for the plug, shown apart from the power supply and casing for ease of illustration; and,

(Continued)

FIG. 22 is a front perspective view of the design for the plug, shown apart from the power supply and casing for ease of illustration.
